UNITED STATES PATENT OFFICE

99,993

DESIGN FOR TOASTED BREAD

William H. Brooks, Fairfax, Calif.

Application April 14, 1936, Serial No. 62,118

Term of patent 14 years

To all whom it may concern:

Be it known that I, William H. Brooks, a citizen of the United States, residing at Fairfax, county of Marin, State of California, have invented a new, original, and ornamental Design for Toasted Bread, of which the following is a specification, reference being had to the accompanying drawing, forming part thereof.

Fig. 1 is a front view of a piece of toasted bread showing my new design; and

Fig. 2 is a sectional view taken on line II—II of Fig. 1.

The two faces of the toast are practically identical in appearance, and the opposite side is, therefore, the same as the front view, as shown in Fig. 1.

I claim:

The ornamental design for toasted bread, substantially as shown and described.

WILLIAM H. BROOKS.
